UNITED STATES PATENT OFFICE

2,474,905

BLASTING MAT

Joseph S. Mazzella, New York, N. Y.

Application July 2, 1948, Serial No. 36,587

1 Claim. (Cl. 139—425)

1

This invention relates to blasting mats, and aims to provide a novel, practical and useful sturdy mat suitable for use in blasting work, which is at the same time capable of withstanding repeated use.

Another object of the invention is the provision of a blasting mat out of a single length of wire rope or cable, which is threaded into a pattern to form a strong, durable and tough mat.

The above broad as well as additional and more specific objects will become apparent in the following description, wherein characters of reference refer to like-numbered parts in the accompanying drawings. It is to be noted that the drawings are intended solely for the purpose of illustration, and that it is neither desired nor intended to limit the invention necessarily to the exact details of construction shown except insofar as they may be deemed essential to the invention.

Referring briefly to the drawings, Fig. 1 is a diagrammatic plan view of an unfinished blasting mat made in accordance with the principles of this invention and at the same time illustrating the manner of threading or weaving the wire rope to form the mat.

Fig. 2 is a plan view of the actual finished mat.

Fig. 3 is a fragmentary perspective view, partly in diagrammatic form, illustrating two ways in which the warps of the mat may be laid down.

Fig. 4 is a sectional view taken on the line 4—4 of Fig. 3.

Fig. 5 is a sectional view in general similar to the left-hand portion of Fig. 4, but taken after the warps have been completely laid down and the first pair of woofs have been inserted.

Fig. 6 is a view similar to Fig. 5, but showing the first two pairs of woofs laid down and the manner of using the slat or board to force the third pair of woofs into position; the slat is thus used, however, in forcing every pair except possibly the last pair, of woofs into position.

Fig. 7 is a view similar to Fig. 4, taken, however, through the finished mat.

Fig. 8 is a fragmentary enlargement of Fig. 3.

Fig. 9 is a sectional view taken on the line 9—9 of Fig. 2.

Referring in detail to the drawings, the numeral 10 indicates a finished blasting mat embodying this invention, which is substantially rectangular in outline. The mat is formed of a single length of wire rope or cable, and although this wire rope or cable is shown at 11 as a solid wire, in practice stranded wire is generally used.

A pair of slats or boards 13 and 14 are utilized, and they are laid on the floor or on supports, not

2

shown, to elevate them somewhat above the floor, and they may be releasably held in spaced parallel relationship by means of pegs 19 secured to or nailed to the floor. The wire 11 may be looped about the boards 13 and 14 to form the warps 12 in the manner shown in the upper portion of Fig. 3, that is, by alternately passing the rope over both boards and under both boards, or it may be looped about the boards in the "figure 8" fashion shown in the lower portion of Fig. 3 to form warps 20. The spacing of the boards 13 and 14 determines the length of the mat.

The woofs 17, which are formed of the same length of rope 11 after completion of the warps 12, are formed as follows. The two end warps are shown at 12a and 12b in Fig. 2. The continuing length of wire which is on hand from each of these end warp threads is used to form the woofs 17a and 17b at the bottom, Fig. 2, by threading the two rope ends through the warps in mutually opposite directions, as shown by the arrows, Fig. 2. After passing the rope ends all the way through, they are turned back to form bights 18a and 18b and they are again passed through in the opposite directions indicated by the arrows to form the next pair of woofs 17c and 17d. This is repeated for successive pairs of woofs 17 throughout the width of the mat, with the free ends of the rope emerging at opposite ends of the mat at 17e and 17f. The free ends are secured by couplings or other suitable means, 21, to end bights 18, as shown in Figs. 2 and 9.

To facilitate the weaving of the woofs, the method illustrated in Figs. 5 and 6 is carried out, owing to the relative heaviness of the wire rope used. The first two woofs 17a and 17b may be threaded through the warps while the board 13 is in position against the bights 16, as shown in Fig. 5. Then that board 13 is pulled out and reinserted on the right-hand side of the woofs 17a and 17b, as shown in broken lines, and then by pushing the board 13 to the left it will raise the woofs 17a and 17b against the bights 16; however, a second board 13 could be used for insertion into the position shown in broken lines in Fig. 5 before the first board 13 shown in full lines is removed.

After the first two woofs 17a and 17b have thus been positioned against the bights 16, the board 13 is removed and reinserted after crossing the upper and lower warps 12 to form a closed loop 22 about the said end woof. This step is not illustrated, but in Fig. 6 the same step is illustrated in the case of the third pair of woofs 17 after the second successive loop 23 has been

formed to enclose the second pair of woofs 17c and 17d. Continuing after the forcing of the said third pair of woofs 17 into position by the board 13 and thus forming the second loop 23, the board 13 is again removed, the warps 12 are again crossed in the same manner, and from there the procedure is continued throughout the width of the mat as the woofs are woven through the warps. A completed fragment of the mat, in cross-section, is shown in Fig. 7.

It is to be noted that the woofs 17 are grouped in pairs, of which the pairs 17a, 17b and 17c, 17d are examples. The two threads of each such pair pass alternately over and under successive warps 12. However, each such pair of warps 17 passes under the warps 12 over which its two neighboring pairs of warps 17 have passed over, and vice versa. For instance, the two woofs 17a, 17b pass over the warps 12c and under the next warp 12d, whereas the next two woofs 17c, 17d pass under the warp 12c and over the warp 12d next adjacent thereto.

A blasting mat thus made is found to be of tough and durable construction. In the various views of the drawings, particularly Fig. 2, it is to be understood that all of the strands shown are spaced apart at exaggerated distances, and this is done for the sake of clarity; but in practice and in the actual finished mat the strands would be packed close together.

I claim:

The method of weaving a mat out of a unitary length of rope consisting in forming the warps out of the intermediate portion thereof in substantially parallel rows thereby having said warps joined by bights at their ends and having end lengths of the rope left over, in forming woofs out of said end lengths by passing said end lengths beginning at one end of the mat alternately over and under said warps in mutually opposite directions and upon the completion of one of said woofs doubling back said end lengths and passing the same alternately under and over said warps in the opposite directions and then doubling back said end lengths again and proceeding in the same manner to weave said woofs through the entire length of the mat.

JOSEPH S. MAZZELLA.
